UNITED STATES PATENT OFFICE.

WILLIAM ESTY, OF LACONIA, NEW HAMPSHIRE.

DESIGN FOR A VALVE-SUPPORT.

SPECIFICATION forming part of Design No. 26,256, dated November 10, 1896.

Application filed October 12, 1896. Serial No. 608,665. Term of patent 14 years.

To all whom it may concern:

Be it known that I, WILLIAM ESTY, a citizen of the United States, residing at Laconia, in the county of Belknap and State of New Hampshire, have invented and produced a new and original Design for a Valve-Support for Automatic Fire-Extinguishers, of which the following is a specification, reference being had therein to the accompanying drawings.

Figure 1 shows in side elevation, and Fig. 2 in end view, a valve-support embodying my design.

The leading feature of my design is the resemblance which the same presents in side elevation to an isosceles triangle, the latter having an incurved base. The said isosceles tri-

angle is marked by a bisecting line extending from the apex to the base thereof, and also by ribs or flanges projecting laterally along the bisecting line.

Having thus fully described my design, what I claim, and desire to secure by Letters Patent, is—

The design for the valve-support of an automatic fire-extinguisher, substantially as shown.

In testimony whereof I affix my signature in presence of two witnesses.

WILLIAM ESTY.
